UNITED STATES PATENT OFFICE.

HARRY SOLOMON, OF ST. JOSEPH, MISSOURI.

TOWEL-CABINET.

Specification of Letters Patent.

Patented Apr. 8, 1919.

1,299,630.

Application filed July 28, 1915, Serial No. 42,341. Renewed December 12, 1918. Serial No. 266,516.

To all whom it may concern:

Be it known that I, HARRY SOLOMON, a citizen of the United States, residing at St. Joseph, in the county of Buchanan and State of Missouri, have invented certain new and useful Improvements in Towel-Cabinets, of which the following is a specification.

The invention relates to improvements in 10 towel cabinets.

The object of the present invention is to improve the construction of towel cabinets and to provide a simple, inexpensive and practical towel cabinet of strong and durable construction designed for use in laboratories of hotels, hospitals, public buildings and various other places where it is desired to supply individual towels and adapted to hold a relatively large number of clean 15 towels and maintain the same in a sanitary condition and equipped with means for exposing only a portion of the top towel of a stack and of enabling the towels to be removed one at a time without mussing or 20 disarranging the clean towels contained within the cabinet, whereby an absolutely fresh and spotless sanitary towel is supplied to each person.

A further object of the invention is to 30 provide a towel cabinet of this character adapted to maintain clean and soiled towels separate and capable of admitting free and convenient use of the towels without permitting the same to be removed from the 35 cabinet, whereby loss and abuse of the towels are effectually prevented.

It is also an object of the invention to 40 provide an ornamental fire and germ proof cabinet, which will be perfectly ventilated and which will afford ready access to the soiled towel compartment to permit convenient removal of the soiled towels and easy loading of the cabinet with clean towels.

With these and other objects in view the 45 invention consists in the construction and arrangement of parts hereinafter fully described, illustrated in the accompanying drawings and pointed out in the claims hereto appended, it being understood that 50 various changes in the form, proportion and minor details of construction, within the scope of the claims, may be resorted to with-

out departing from the spirit or sacrificing any of the advantages of the invention.

In the drawings:—

Fig. 1 is a front elevation of a towel cabinet constructed in accordance with this invention, the cabinet being arranged for use.

Fig. 2 is a similar view, the hinged front 60 being open and the parts being arranged for loading.

Fig. 3 is a central vertical sectional view of the cabinet, the parts being arranged as shown in Fig. 1.

Fig. 4 is a horizontal sectional view on the line 4—4 of Fig. 3.

Fig. 5 is a perspective view of the following rod and adjacent portions.

Fig. 6 is a detail perspective view of the 70 loader plate.

Fig. 7 is a detail view of the loader tube.

Fig. 8 is a fragmentary view partly in section showing the manner in which the clean towels are arranged inside the frame.

Like numerals of reference designate corresponding parts in the several figures of the drawings.

In the accompanying drawings in which is illustrated the preferred embodiment of 80 the invention, 1 designates a cabinet or case

designed to be constructed of any suitable material preferably sheet steel and comprising spaced vertical side walls 2, a rear vertical wall 3, horizontal top and bottom 85 walls 4 and 5 and an outwardly bowed approximately semi-cylindrical front wall or door 6 hinged at one of its vertical edges at

7 and pivoted at its free vertical edges with suitable locking means as shown at 8. The 90 hinged door 6 terminates at a point intermediate of the top and bottom of the cabinet to leave an exposed towel compartment

9 which is protected and closed at the front by the means hereinafter described when the 95 cabinet is in use. The cabinet is equipped

with rollers 10, which support the bottom 5 of the cabinet above the floor to enable it to be easily moved and to permit free ventilation through the bottom openings 11 pro-

vided for this purpose. The lower portion 100 of the cabinet constitutes a soiled towel compartment 12 and the cabinet is relatively long to provide ample space for a large

number of soiled towels to prevent the same from bunching and interfering with the free dropping of all the towels into the compartment 12.

- 5 The clean towels 13 are arranged in a stack and are supported upon a platform 14 constructed of sheet metal or other suitable material and preferably provided at opposite sides with horizontal pivots 15 journaled in suitable bearing 16 at the side walls 2 of the cabinet, but a relatively fixed platform or shelf may be used. The pivots enable the clean towels to adjust themselves automatically and permit a perfect feeding 10 of towels and a combined follower and slideable front section 17 and a lower curtain 18, which are guided in suitable ways 19 located at opposite sides of the cabinet. The guides or ways 19 preferably consist of metal strips 20 secured to the inner faces of the side walls 2 and coöperating with the upper portions of the front flanges 20 of the said side walls. The upper portion of the guides or ways 19 are vertical and the lower portions 21 are 25 inclined and extend downwardly and rearwardly to carry the curtain clear of the soiled towels and permit ready removal of the same when the curtain is in the lowered position.
- 30 The slideable upper front section or follower 17 which is constructed of sheet metal or other suitable material, is provided at the lower end with a central recess 17^a to expose the top towel of the stack and enable 35 the same to be drawn out of the cabinet and it carries a follower frame or member 22 consisting of a horizontal rod having terminal attaching portions 23 and provided at its central portion with a rearwardly extending 40 approximately W-shaped towel engaging loop 24 adapted to rest upon the top of the stack of towels and permit only one to be removed when the top one is pulled outward through the recess or opening 17^a of the follower. The attached terminals of the follower frame extend upward at the rear face of the follower 17 and are riveted or otherwise secured to the same. The follower frame is also provided with transversely 45 depending loops 25 forming hinge elements and adapted to receive a removable horizontal pivot rod 26 which connects the curtain to the follower 17. The curtain which is 50 constructed of flexible sheet metal or other suitable material is provided at the top with a hinge element or eye preferably consisting of a head 27 formed by rolling a portion of the upper edge of the curtain. The horizontal pivot or connecting rod is placed in 55 the eyes or hinge elements of the follower and the curtain when these parts are at the limit of their upward movement and the cabinet is provided with a suitable opening 60 28 in its side wall for this purpose.

Each towel when ironed is folded with 65 one end 29 projecting beyond the folds and such projecting end is equipped with an eye 30 reinforced with metal or other suitable means and adapted to have a guide rod 31 passed through it to prevent the towels from 70 being removed from the cabinet by the individual user. Any kind of towel may of course be employed and if desired the towels may be done up in separate envelops or packages to insure a sanitary condition of 75 the same.

The guide rod 31 is composed of front and rear vertical portions, a forwardly connecting approximately U-shaped connecting loop 34 and a lower downwardly and rearwardly extending inclined portion 35 forming a lower extension of the front vertical portion 33. The rear vertical portion 32 which passes through the alined eyes 30 of the stack or pile of towels extends downwardly through an opening 36 in the towel platform or support 14 and is also arranged in an angular bend 37 of one side of the towel engaging loop 24 of the frame or member 22. The loop 34 90 extends outwardly through the opening 17^a of the follower and enables the upper most towel of the stack to be drawn outwardly through the said opening 17^a to the front of the cabinet in convenient position 95 for use on both the face and hands without requiring the person using it to assume an inclined position. After the towel has been used it is allowed to drop into the top of the hinged front or door and it is guided 100 into the lower portion of the cabinet by the front portion of the guide rod, which automatically adjusts itself to the diminishing size of the stack of towels to maintain the top loop 34 at the opening 17^a of the follower. The lower inclined portion 35 of 105 the guide rod carries or guides the towels to the rear portion of the soiled towel compartment. The soiled towels are retained on the inclined portion 35 by a nut 38 and the rear vertical portion is provided at its lower end with a padlock 39 to prevent surreptitious removal of the guide rod.

The follower and the curtain close the front of the clean towel compartment and 115 automatically adjust themselves to the diminishing size of the stack of towels and they also maintain the stack in proper condition. The curtain is provided with a central longitudinal opening 40 through which the rear vertical portion 32 of the guide rod extends and which permits the curtain to be raised and lowered independently of the 120 guide rod.

In loading the cabinet the stack of towels 125 is placed upon a loading plate 41 and a tube 42 is passed through the eyes of the towels and through a slot 43 in the loader plate and

the opening 36 in the towel platform 14. The guide rod 31 is then inserted in the tube which is withdrawn from the stack of towels by pulling it downward through the slot in the curtain. The loader plate is then withdrawn and the curtain is connected to the follower by the rod 26 and the cabinet is ready for use. The loader plate is provided at the front with a flange 41^a and the slot 10 extends to the rear end of the loader plate to permit the withdrawal of the said plate.

The hinged front or door 6 is equipped with a guard or closure 44 consisting of a substantially oblong plate provided at its 15 ends with pivots 45 preferably formed by a rod 46 and arranged in suitable bearings at the side portions of the hinged front or door 6. This plate which is rounded at the ends as at 47 to conform to the configuration of the hinged front 6 is located slightly 20 below the top thereof to clear a top flange 48 thereof and it is perfectly balanced and is adapted to be tilted or rotated by a towel to permit the same to readily enter the cabinet. The guard or closure is also provided 25 at the center with opposite slots or recesses to receive the front portion of the guide rod.

What is claimed is:—

1. A cabinet of the class described having 30 a compartment open at the front and adapted to hold a stack of towels, guides located at opposite sides of the cabinet and extending from the top of the compartment to a point below the bottom of the same, the 35 lower portions of the guides being inclined downwardly and rearwardly, a front section, a member slidable in the guides to close the space above the towels, and a curtain hinged to the front section or member and slid able in the guides to close the space occupied by 40 the towels and adapted to move downward in the inclined portion of the guides.

2. A cabinet of the class described having a compartment open at the front and adapted 45 to receive a stack of towels, a follower adapted to rest upon the towels and a curtain connected with the follower and depending therefrom to close the space occupied by the towels.

50 3. A cabinet of the class described having a compartment open at the front and adapted to receive a stack of towels, guides located at opposite sides of the compartment, a follower supported by the towels, and a curtain 55 slid able in guides and connected with and depending from the follower to close the space occupied by the towels.

4. A cabinet of the class described having a compartment open at the front and adapted 60 to receive a stack of towels, guides located at opposite sides of the compartment, the lower portion of the guides being extended downwardly and rearwardly, a follower supported by the stack of towels, and a curtain

tain slid able in the guides and hinged at 65 the top to the follower so as to move in the lower portion of the guides.

5. A cabinet of the class described including a lower soiled towel compartment, a pivoted platform adapted to support a stack 70 of towels, and guiding means for the towels passing through the platform and extending therefrom to the soiled towel compartment, said guiding means being adapted to steady the platform and the latter being adapted to 75 adjust itself automatically to the towels.

6. A cabinet of the class described having an upper clean towel compartment and a lower soiled towel compartment, a follower 80 adapted to rest upon the towels, a curtain connected with the follower and having a longitudinal slot, and a guide rod for the towels having an inner portion extending through the slot.

7. A cabinet of the class described having 85 a compartment open at the front and adapted to hold a stack of towels, a slid able front section for closing the space above the towels, and a follower frame carried by the said section and arranged upon the stack of 90 towels.

8. A cabinet of the class described having a compartment open at the front and adapted to hold a stack of towels, a slid able front section for closing the space above the 95 towels, and a follower frame carried by the said section and having a rearwardly extending loop adapted to rest upon the stack of towels.

9. A cabinet of the class described having 100 a compartment open at the front and adapted to hold a stack of towels, a slid able front section for closing the space above the towels, a follower frame carried by the said section and having a rearwardly extending 105 loop adapted to rest upon the stack of towels, one side of the loop having an offset bend and a guide rod for the towels located at the bend and extending through the bottom of the upper compartment.

10. A cabinet of the class described having a compartment open at the front and adapted to hold a stack of towels, a slid able front section for closing the space above the towels, and a follower frame carried by the said section and arranged upon the stack of towels, and a curtain located in front of the towels and connected at the top to the said frame.

11. A cabinet of the class described having a compartment open at the front and 115 adapted to hold a stack of towels, a slid able front section for closing the space above the towels, a follower frame carried by the said section and consisting of a rod, having a rearwardly extending loop arranged to rest 120 upon the towels, said rod having depending loops, a curtain located in front of the towels, and a horizontal rod arranged in the

depending loop and connecting the curtain to the follower frame.

12. A cabinet of the class described including a loader plate having a slot, and a 5 tube adapted to extend through the loader plate and receive a guide rod.

In testimony whereof I affix my signature in the presence of two witnesses.
